ATTORNEYS

UNITED STATES PATENT OFFICE

PERCY C. FINLEY, OF LOS ANGELES, CALIFORNIA

TRAFFIC BUTTON

Application filed July 23, 1928. Serial No. 294,805.

This invention relates to devices commonly called traffic buttons.

An object of the invention is to provide an improved traffic button which is vertically 5 depressible, so that when the body or head of the button is encountered by a wheel of a vehicle, it may be depressed and assume a position approximately flush with the surface of a roadway, and in this manner it will 10 not act as an obstruction to the wheel. Most forms of traffic buttons now in general use are the solid or stationary character, and because of this, when encountered by wheels of vehicles, they result in damage to tires and 15 to the wheel. It is well known that striking these traffic buttons is not due to reckless or careless driving, but frequently results from unavoidable circumstances, and it not infrequently occurs when conditions are right that 20 vehicles are often turned over on encountering them.

Another object of the invention is, therefore, to provide a traffic button which is of a disappearing nature so that if the button 25 should be struck by the wheel of a vehicle, it will disappear beneath the surface of the roadway, and the above recited disadvantages of the solid or stationary type of button will not be present.

30 A further object of the invention is to provide an improved traffic button which is of simple, cheap and durable construction, and which can be easily and quickly installed, and which will present an appearance somewhat 35 similar to traffic buttons now in general use.

With the foregoing and other objects in view, which will be made manifest in the following detailed construction and specifically pointed out in the appended claims, reference is had to the accompanying drawings 40 for an illustrated embodiment of the invention, wherein

Figure 1 is a top plan view of the improved traffic button;

45 Fig. 2 is a vertical section taken substantially upon the line 2—2 of Fig. 1;

Fig. 3 is a horizontal section taken substantially upon the line 3—3 of Fig. 2.

50 Referring to the accompanying drawings wherein similar reference characters desig-

nate similar parts throughout, the improved button consists of a housing 10 in the form of an open topped cylindrical container having a bottom 11. A dome shaped body or head 12 fits within the housing 10 and is vertically 55 slideable therein. Central of the dome shaped body, and on the under side thereof, there is a depending guide pin 13 provided with a shoulder 14 which bears against the under side of the dome shaped body. The 60 upper end of the guide pin is threaded into the body 12, as indicated at 15, and its top is preferably flush with the body. Central of the bottom 11 of the housing 10 there is preferably 65 formed an upstanding boss 16 which may, if desired, be reinforced by ribs 17. On the under side of the bottom 11 there is also a boss 18 in alignment with the boss 16, and a bore 19 extends through both posts and receives the lower end of the guide pin 13. 70 A washer 20 fits about the guide pin and is preferably recessed in the top of the upper boss 16, constituting a spring seat for a coil spring 21 which is compressed about the 75 guide pin between the washer 20 and the shoulder 14 serving to urge the dome shaped body 12 into its uppermost position, protruding out of the top of the housing 10.

A retaining ring 22 is fastened to the top of the housing, such as by bolts or cap screws 23, which have their heads disposed in recesses 24 therein. This retaining ring extends inwardly beyond the side walls of the housing and fits in a groove 25 formed on the dome shaped member 12, and serves to limit the 80 upward movement of the dome shaped member, due to the action of the spring 21. Around the bottom of the dome shaped member there is formed a depending flange 26 which, when the dome shaped member is depressed into the housing, is adapted to engage and rest on the bottom 11, thus limiting the 85 downward movement of the dome shaped body 12.

90 It will be noted that adjacent the edge of the exposed surface of the body 12 there is an annular concave area indicated at 27, the particulars of which will be hereinafter more fully explained. The housing 10 is adapted to be imbedded in a roadway R so that the 95 100

top surface of the retaining ring 22 is approximately flush with the surface of the roadway.

The improved traffic button serves as an indicator in identically the same fashion as those traffic buttons now in general use. However, if a wheel of a vehicle should strike the button, instead of encountering a stationary obstruction, the dome shaped body 12 is depressed, slideable vertically downward within the housing, and the guide pin 13 sliding downwardly through the bosses 16 and 18, compressing the spring 21. When the dome shaped body 12 is in its most depressed position, the flange 26 rests on the bottom 11, and in this manner the body is amply sufficient to support the weight of any vehicle passing over the traffic button. In such position, the top surface of the body 12 and of the guide pin 13 is substantially flush with the top surface of the retaining ring 22 and the roadway R, and although there is a small space in such position between the top of the body of the retaining ring 22, a vehicle on passing over the button, will not receive an objectionable jar, the space being too small to have such jar created.

As soon as the wheel is passed over the body, the spring 21 serves to return the body into its normal position, as shown in Fig. 2, wherein the body projects above the surface of the roadway and serves as an indicator.

The function of the concave annular area 27 is as follows: As the wheel of the vehicle strikes the dome shaped member, the outermost part of the concave area being nearly horizontal, allows the wheel to force the dome shaped member vertically downward and there is very little tendency to knock the body 12 sideways so that it will bind within the housing. Also, in the case of a vehicle skidding laterally, the concave area 27 enables the tire of the vehicle wheel to slide upwardly on to the body 12 and thus press the body downwardly. Whereas, if the body 12 presented a convex surface over its entire top, there would be a tendency to have the body move sideways within the housing and bind.

From the above described construction it will be appreciated that an improved traffic button is provided which presents an appearance similar to that of traffic buttons now in general use. Furthermore, the improved traffic button is of a disappearing nature, so that it will not offer a solid stationary obstruction to vehicles passing over it.

Various changes may be made in the details of construction by those skilled in the art, without departing from the spirit and scope of the invention as defined by the appended claims.

I claim:

1. A traffic button comprising a dome shaped body adapted to be mounted in a roadway to serve as an indicator, means urging

said body to assume a normal position above the surface of the roadway, said means permitting said body to be vertically depressed so that it will not act as an obstruction when encountered by wheels of a vehicle, said dome shaped body presenting an annular concave surface adjacent its base as and for the purpose described. 70

2. A traffic button comprising an open topped housing adapted to be imbedded in a roadway, a dome shaped body vertically movable in said housing adapted to assume a normal position projecting through the open top of the housing, means urging the dome shaped body into said normal position, but permitting it to be depressed into said housing, and a retaining ring detachably secured to the top of the housing and engageable upon the dome shaped body for limiting the upward movement of the dome shaped body. 80

3. A traffic button comprising a dome shaped body adapted to be movably mounted in a roadway for vertical movement, said body presenting an annular concave area near its outer edge, as and for the purpose described. 90

4. A traffic button comprising an open topped cylindrical housing adapted to be imbedded in a roadway, a dome shaped body vertically movable in said housing adapted to assume a normal position projecting through the open top of the housing, spring means urging the dome shaped body into said normal position but permitting it to be depressed into said housing, a retaining ring on top of the housing and engageable upon the dome shaped body for limiting the upward movement of the dome shaped body, said retaining ring being detachably fastened to the top of the housing by bolts having heads recessed in the retaining ring. 100

In testimony whereof I have signed my name to this specification.
